United States Patent

Des. 239,539
Patented Apr. 13, 1976

239,539

LOUDSPEAKER DRIVER UNIT

George R. Wagner, Santa Ana, Calif., assignor to
Altec Corporation, Anaheim, Calif.

Filed Oct. 29, 1974, Ser. No. 518,615

Term of patent 14 years

Int. Cl. D14—01
U.S. Cl. D26—14 G

FIG. 1

FIG. 4

FIG. 2

FIG. 3

FIG. 5

FIG. 6

FIG. 1 is a top plan view of a loudspeaker driver unit, showing my new design;

FIG. 2 is a side elevational view of the driver unit;

FIG. 3 is a side elevational view of the driver unit taken from an angle 90° from the view of FIG. 2;

FIG. 4 is a bottom plan view of the driver unit;

FIG. 5 is a perspective view of the driver unit taken from the top thereof; and

FIG. 6 is a perspective view of the driver unit taken from the bottom thereof.

I claim:

The ornamental design for a loudspeaker driver unit, as shown.
